UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

ELASTIC-FLUID TURBINE.

1,415,571.

Specification of Letters Patent.

Patented May 9, 1922.

Application filed June 29, 1920. Serial No. 392,776.

To all whom it may concern:

Be it known that I, OSCAR JUNGGREN, a citizen of the United States, residing at Schenectady, in the county of Schenectady, State of New York, have invented certain new and useful Improvements in Elastic-Fluid Turbines, of which the following is a specification.

The present invention relates to elastic fluid turbines and has for its object to provide an improved structure and arrangement for supplying elastic fluid to the admission end or first stage of such a machine.

In connection with the operation of elastic fluid turbines it is important and desirable that the turbine shell be always uniformly heated so as to do away with stresses and distortions due to unequal heating thereby keeping the machine strictly in alignment under all conditions of operation and more particularly, an object of my invention is to provide an improved structure which among other things will accomplish this result.

For a consideration of what I believe to be novel and my invention, attention is directed to the accompanying description and the claims appended thereto.

In the drawing, Fig. 1 is a transverse sectional view taken on 1—1 Fig. 2. of a turbine structure embodying my invention; and Fig. 2 is an axial sectional view of the high pressure or admission end of such a structure the section being taken on line 35 2—2, Fig. 1.

Referring to the drawing, 5 indicates the surrounding casing or wall of a turbine, the portion shown being the high pressure or admission end. This end of casing 5 is closed by a head comprising an inwardly dished end wall 6 provided at its periphery with an axially extending wall 7 having a flange 8 at its edge which is bolted to a flange 9 on casing 5. The end head may be 45 cast or otherwise formed as a unitary structure, and at its central portion is provided with an opening through which shaft 10 extends, a suitable packing 10^a being provided between the shaft and the wall of the opening. Fastened on shaft 10 are the bucket carrying element or elements. In the present instance I have illustrated a turbine of the impulse type wherein the casing is divided

into a number of stages by nozzle containing diaphragms, there being one or more 55 bucket wheels in each stage, as this is a type of turbine to which my invention is well adapted. It will be understood, however, that my invention is not necessarily limited to this specific type of machine but may be 60 embodied in any type of machine to which it may be found applicable. The first stage wheel is shown at 11 and it is illustrated as carrying two rings of buckets 12 and 13.

For supplying elastic fluid to the buckets 65 of the first stage wheel, I provide an annular chest 14 which is located within the confines of walls 6 and 7 of the turbine head. Chest 14 is of less diameter than wall 7, and it is mounted in spaced relation to wall 70 7 and also wall 6, in such a manner that it may expand and contract independently of such walls. To this end I provide wall 7 with a number of circumferentially spaced 75 openings 16 which may be surrounded by annular flanges 16^a, and in such openings I rigidly mount tubes 17, the inner ends of which enter openings 18 in the peripheral wall of chest 14. Tubes 17 fit openings 18 with a sliding fit and serve to support the 80 chest in spaced relation to walls 6 and 7 and hold it centered. At the same time, however, the chest is free to expand and contract, the chest sliding on the ends of tubes 17 during radial expansion and contraction.

Some or all of the tubes 17 may be used for admitting elastic fluid to chest 14. In the present instance, four tubes are shown and each is connected by a conduit 19 to a 90 valve chest 20 in which are arranged four valves 21, 22, 23 and 24, one for each conduit 19. Elastic fluid is admitted to valve chest 20 through a conduit 25, and the arrangement is such that valves 21, 22, 23 and 24 95 control the flow of elastic fluid from the valve chest to conduits 19. The stems of the valves are indicated at 26 and they may have suitable manual operating means connected to them or they may be arranged to be 100 opened automatically as is well understood. In any event, the arrangement will be such that the valves are or may be opened successively. Valve chest 20 is supported in spaced relation to the turbine casing by the 105 conduits 19 and it is thus free to expand

and contract independently of the turbine casing; and by having it thus supported such expansion and contraction does not affect the tightness of the pipe joints between 5 the valve chest and the turbine.

Elastic fluid chest 14 has an annular opening 27 on its side adjacent the rings of buckets and fastened over such opening is a nozzle ring 28 for directing the elastic fluid 10 to the first ring of buckets 12. Chest 14 is strengthened at opening 27 by means of ribs 29.

When operating at light loads, the best efficiency is obtained by admitting elastic 15 fluid to the buckets over only a part of the periphery of the wheel, while when operating at heavy loads complete peripheral admission is desirable. To accomplish this result I divide chest 14 by partitions 30 into a 20 plurality of chambers, and in the present instance four chambers 31, 32, 33 and 34 one for each conduit 19 are shown. Each chamber supplies elastic fluid to a definite arc 25 of nozzles, and valves 21, 22, 23 and 24 control the flow of elastic fluid to chambers 31, 32, 33 and 34, respectively. In operation, valve 21 is first opened admitting elastic fluid to chamber 31, thereby supplying elastic fluid to the turbine wheel over the arc 30 spanned by chamber 31. This operates the turbine at light load. As the load becomes greater, valve 22 is then opened, thereby admitting elastic fluid over the arc spanned by both chambers 31 and 32. Following this, 35 valves 23 and 24 are successively opened, complete peripheral admission occurring when all four valves are open, the opening of valves 21, 22 and 23 may represent full load, and the opening of valve 24 overload.

40 In the operation of a multistage impulse turbine the pressure in the first stage rises as the load comes on and this means that the velocity of the elastic fluid issuing from the first stage nozzles decreases. Now with a 45 first stage wheel having two rows of buckets, it is customary to provide between the rows a ring of stationary intermediate buckets, usually termed intermediates, which are carried by the casing and direct the elastic fluid from the first row of buckets to the second row. As is well understood, a part 50 of the velocity of the elastic fluid is extracted by each row of buckets. With a given bucket speed, a certain elastic fluid velocity is required for the most efficient extraction 55 of the energy by the two rows of buckets and if the machine is designed so that at normal load the elastic fluid velocity is such as to give the best efficiency for the given bucket speed, then at a load greater than normal, or overload, the elastic fluid velocity in the 60 first stage will be too low, and as a result the efficiency will be impaired. In fact at overloads, the elastic fluid velocity may be 65 such that its energy can be better extracted

by a single row of buckets than by two rows. With an arrangement as above described therefor I preferably provide intermediates only in front of those portions of the nozzle which are used in operating the turbine up to a certain load, for example, normal load, while for the remainder of the periphery I omit the intermediates altogether. This means in substance that the second row of buckets 13 performs no work 70 at the part of the periphery where the intermediates are omitted, all the energy being extracted by the first row of buckets 12. In the drawing, Fig. 2, I have indicated intermediates at 35, and such intermediates may 75 be located in front of elastic fluid chambers 31, 32 and 33, for example, and omitted before chamber 34; or the intermediates may be omitted before both chambers 33 and 34, the arrangement in any particular instance 80 depending on the design of the machine. By this means I am enabled to increase the efficiency of the machine when operating at certain loads without additional cost or parts, and in fact, at an actual saving for parts are 85 omitted which heretofore have been used.

It will be noted that the elastic fluid chest is supported entirely by the turbine head and it may be assembled therein by placing it within the head and then inserting tubes 95 17. This makes a simple, easy assembly, and also makes it possible to cast the chest entirely in one piece if found desirable. Likewise the head may be cast as one piece.

With the foregoing arrangement it will 100 be seen that since the elastic fluid is admitted to the inner elastic fluid chest it does not come into direct contact with the turbine casing to heat it non-uniformly and this is true whether elastic fluid is being admitted 105 through one, two, three or all of tubes 17. On the other hand, non-uniform heating of fluid chest 14 does not affect the turbine casing, since it is free to expand and contract independently of the turbine casing. In 110 this connection it will be noted that when expanding and contracting, chest 14 slides on the ends of tubes 17 and that the tightness of the joint is not affected.

In accordance with the provisions of the 115 patent statutes, I have described the principle of operation of my invention, together with the apparatus which I now consider to represent the best embodiment thereof, but I desire to have it understood that the apparatus is only illustrative and that the invention may be carried out by other means.

What I claim as new and desire to secure by Letters Patent of the United States, is:—

1. In an elastic fluid turbine, the combination of a casing, an annular elastic fluid chest located therein in spaced relation to the walls thereof, and radially-projecting, circumferentially-spaced, telescoping members carried by the casing and chest which 125 130

have sliding engagement with each other and form a support for said chest whereby it is free to expand and contract radially in all directions.

5 2. In an elastic fluid turbine, the combination of a casing, an annular elastic fluid chest located therein in spaced relation to the walls thereof, said chest being provided with circumferentially-spaced openings, and

10 radially-projecting tubes carried by said casing, the ends of said tubes having sliding engagement with said openings and forming a support for said chest, whereby the chest is free to expand and contract radially in all

15 directions.

3. In an elastic fluid turbine, the combination of a casing, an annular elastic fluid chest located therein in spaced relation to the walls thereof, said chest being provided

20 with circumferentially-spaced openings, radially-projecting tubes carried by said casing, the ends of said tubes having sliding engagement with said openings and forming a support for said chest, whereby the chest

25 is free to expand and contract radially in all directions, and means for supplying elastic fluid through at least some of said tubes to said chest.

4. In an elastic fluid turbine, the combination of a casing, a head for the high pressure end, said head comprising walls which define an annular recess, an annular elastic fluid chest in said recess, circumferentially-spaced, radially-projecting, telescoping

35 members carried by said head and chest which have sliding engagement with each other and form a support for holding said chest in spaced relation to the walls of the head but permit the chest to expand and contract independently of the head.

5. In an elastic fluid turbine, the combination of a casing, a head for the high pressure end, said head comprising walls which form an annular recess, an annular fluid chest in

45 said recess, circumferentially spaced tubes which extend through openings in said head and are fixed therein, said chest being slid-

ably supported on the ends of said tubes in spaced relation to said head, conduits for supplying elastic fluid to said tubes, and 50 valve means in said conduits.

6. In an elastic fluid turbine, the combination of a casing, a head for the high pressure end, said head comprising walls which form an annular recess, an annular fluid 55 chest in said recess, circumferentially spaced tubes which extend through openings in said head and are fixed therein, said chest being slidably supported on the ends of said tubes in spaced relation to said head, whereby it 60 is free to expand and contract in all directions, conduits for supplying elastic fluid to said tubes, valve means in said conduits, and partition members which divide said fluid chest into arcuate chambers with which said 65 tubes communicate.

7. In an elastic fluid turbine, the combination of a casing, a rotor therein having a plurality of rows of buckets, an annular elastic fluid chest having nozzles for supplying elastic fluid to said buckets, partition members dividing said chest into arcuate chambers, tubes carried by the casing which support said chest in spaced relation to the casing, said tubes serving to supply elastic 75 fluid to the arcuate chambers, and stationary intermediates between the rows of buckets in front of some of said arcuate chambers, there being no intermediates between the rows of buckets in front of other of said 80 arcuate chambers.

8. In an elastic fluid turbine, the combination of a casing, an annular fluid chest therein, tubes carried by the casing and projecting radially inward, said chest being 85 slidably supported on the inner ends of said tubes so it may slide thereon when it expands and contracts, conduits for conveying elastic fluid to said tubes, and a valve chest supported on said conduits. 90

In witness whereof, I have hereunto set my hand this 28th day of June, 1920.

OSCAR JUNGGREN.
